US00D824956S

(12) **United States Design Patent** (10) Patent No.: **US D824,956 S**
(45) Date of Patent: ** Aug. 7, 2018

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Christopher Foss**, San Francisco, CA (US); **Chanaka Karunamuni**, Cupertino, CA (US); **Martin Pedrick**, San Francisco, CA (US); **Wan Si Wan**, Sunnyvale, CA (US)
(73) Assignee: **Apple Inc.**, Cupertino, CA (US)
(**) Term: **15 Years**
(21) Appl. No.: **29/603,277**
(22) Filed: **May 8, 2017**

Related U.S. Application Data

- (63) Continuation of application No. 29/576,140, filed on Aug. 31, 2016, now Pat. No. Des. 786,294, which is a continuation of application No. 29/541,138, filed on Sep. 30, 2015, now Pat. No. Des. 765,711, and a continuation of application No. 29/541,140, filed on Sep. 30, 2015, now Pat. No. Des. 768,181, said application No. 29/541,138 is a continuation of application No. 29/457,361, filed on Jun. 10, 2013, now Pat. No. Des. 741,350, said application No. 29/541,140 is a continuation of application No. 29/457,361.

CLAIM

The ornamental design for a display screen or portion thereof with graphical user interface, as shown and described.

DESCRIPTION

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.

1 Claim, 1 Drawing Sheet
